UNITED STATES PATENT OFFICE.

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK.

DESIGN FOR A BRACE FOR ELECTRIC-LIGHT FIXTURES.

Application filed January 21, 1929. Serial No. 29,711. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for a Brace for Electric-Light Fixtures, of which the following is a specification, reference being had to the accompanying drawing, forming part thereof.

In said drawing:

Figure 1 is a plan view of a brace for electric light fixtures embodying my new design.

Figure 2 is a side elevation of the same.

I claim:

The ornamental design for a brace for electric light fixtures, as shown and described.

GUSTAVE E. VILLARET.
